UNITED STATES PATENT OFFICE.

THOMAS D. HOOPER, JR., OF PHILADELPHIA, PENNSYLVANIA.

AMUSEMENT APPARATUS.

1,101,630.

Specification of Letters Patent. Patented June 30, 1914.

Application filed November 13, 1913. Serial No. 808,386.

To all whom it may concern:

Be it known that I, THOMAS D. HOOPER, Jr., a citizen of the United States, residing at Philadelphia, county of Philadelphia, and 5 State of Pennsylvania, have invented a certain new and useful Improved Amusement Apparatus, of which the following is a specification.

This invention, broadly stated, relates to 10 that class of amusement apparatus commonly known as scenic railways, and has for its principal object to provide an amusement apparatus of this class, the inclines of which are provided with double tracks, each set of 15 tracks alternately equipped at intervals with cut-outs or loops so that when a passenger car having swiveled trucks, passes thereover under the influence of gravity, the car is caused automatically to reverse itself bodily 20 without changing its course of transit, thereby producing a sensation, both novel and exhilarating in its effects.

A further object of the present invention resides in the providing of specially designed 25 passenger cars and in the providing of certain novel construction and arrangement of parts for imparting this rotative movement to the passenger conveyances.

Other and further objects of the present 30 invention reside in the providing of general details of construction and arrangement of parts as will hereinafter more fully appear.

The invention consists of the improvements hereinafter described and finally 35 claimed.

The nature, characteristic features and scope of the invention will be more fully understood from the following description taken in connection with the accompanying 40 drawings forming part hereof and in which: Figure 1, is a perspective view of the amusement apparatus embodying the invention, the view being somewhat diagrammatic in form. Fig. 2, is a top or plan view drawn 45 to an enlarged scale of one of the cut-outs or loops, shown in Fig. 1. Fig. 3, is a fragmentary view, in plan, of a portion of Fig. 2, enlarged and illustrating two positions of a passenger conveyance, and Fig. 4, 50 is a view in section taken approximately on the line 4—4 of Fig. 3.

Referring to the drawings, there is disclosed a physical embodiment of the invention constructed in a manner best known to 55 me at this time for practising the invention. Obviously, various details of construction

and arrangement of parts may be altered and modified to effect the same result without departing from the spirit of the invention. While the following description will be restricted to a scenic railway, I have in mind embodying the idea in the form of a toy.

In the drawings, the supporting structure 10, may be of any suitable construction, designed along the lines now employed in erecting scenic railways. Carried by the supporting structure 10, are inclines 11, of which the number is immaterial. The various inclines 11, are provided with a double set of traction rails 12, and 13, forming in effect a straightaway single track, each set of rails however, being alternately extended at intervals upon arcs of circles to form cut-outs or loops 14. The intersecting points of 75 the two sets of rails at the cut-outs or loops 14, form frogs 15, see Figs. 2 and 3. The rails adjacent the frogs 15, are provided with guards 16. Adapted for travel over the inclines 11, under the influence of gravity are passenger conveyances or cars 17, of any appropriate design. Each passenger car 17, is provided with two swiveled trucks 18, of any suitable construction, 19, designating the swivel connection. Between each 35 truck 18, and the bottom of the car 17, are superimposed, concentrically arranged, rings 20, to afford a good bearing point, upon which the car body may turn. The traction wheels 21, of which there are four for each 40 truck, are flanged as shown, and in practice are adapted to so track upon the rails 12, and 13, that the wheels of a rear truck are always accommodated by the straight section of rails and the wheels of a front truck 45 are always accommodated by the rails extended into cut-outs or loops. By reason of the fact that the straight sections of rails 12, and 13, are closely adjacent one another, and because of the fact that the body of the car 50 has swiveled relation with the trucks, this arrangement is possible, the body of the car assuming a slight angular position, as shown at the right hand side of Fig. 3, when a car 55 is traveling over the straight sections of 100 track.

The operation of the above described apparatus is as follows: A car being in position upon the rails 12, and 13, as just described, passengers are permitted to enter 110 the car at the point 22, and the car is mechanically moved up the incline 23, by suit-

able mechanism, for instance, by means of a cable 24, operated by a motor 25. Upon reaching the point 26, of the amusement apparatus, the car through the force of gravity moves along the inclines 11, until a cut-out or loop 14, is reached. At this point, the wheels of the rear truck of the car continue along the rails which constitute the straightaway portion of the track, and the 10 wheels of the front truck follow the rails, which at this point are curved upon an arc of a circle, and the momentum of the car taken in connection with the length of the curved section of rail over the straight rails, 15 throws the rear of the car together with its complementary truck forwardly ahead of the front truck, which position is shown at the left hand side of Fig. 3. Thus, throughout a portion of the ride over a cut-out or loop, 20 the car 17, ranges crosswise of the track. As the car nears the end of the loop, the rear truck is so far in advance of the front truck as to automatically reverse the car, bodily, without changing its course of transit. 25 and the rear truck is now traveling in advance of what was originally the front truck. Thus as the car once more travels over the straightaway track the passengers are seated backward. Upon the car reaching the 30 next cut-out or loop, the above operation is repeated and again the car automatically reverses itself, bodily, and the passengers are again seated looking forward. This reversing operation may be repeated as 35 often as desired.

In order to guard against accidents, the rails 12, and 13, are provided with guard rails 27, see Fig. 4, but for the sake of clearness, are not shown in the other figures. 40 Other safety appliances, not shown in the drawings, may also be present for guarding against accidents.

What I claim is:

1. In an amusement apparatus, an incline 45 provided with traction rails, which rails are alternately extended at intervals to form cut-outs or loops, a car equipped with swiveled trucks, the traction wheels of which are adapted for travel over said rails under 50 the influence of gravity, the wheels so tracking the rails that upon reaching a cut-out or loop, the car is caused to reverse itself bodily without changing its course of transit.

2. In an amusement apparatus, an incline 55 provided with traction rails, which rails are alternately extended at intervals to form

cut-outs or loops, a car equipped with swiveled trucks, the traction wheels of which are adapted for travel over said rails under the influence of gravity, the wheels so tracking the rails that upon reaching a cut-out or loop, the car is caused to automatically reverse itself bodily without changing its course of transit.

3. In an amusement apparatus, an incline 65 provided with a double set of traction rails of which each set of rails is alternately extended at intervals upon arcs of circles to form loops, a car equipped with swiveled trucks, the traction rails of which are adapted for travel over said rails under the influence of gravity, a set of wheels tracking upon each set of rails, whereby upon reaching a loop, a car is caused to automatically reverse itself bodily without changing its 70 course of transit.

4. In an amusement apparatus, an incline 75 provided with a double set of traction rails, of which each set is alternately extended at intervals upon arcs of circles to form loops, the intersecting points of the two sets of rails forming frogs, a car equipped with swiveled trucks, the traction wheels of which are adapted for travel over said rails under the influence of gravity, a set of 80 wheels tracking upon each set of rails, whereby upon reaching a loop, a car is caused to automatically reverse itself bodily without changing its course of transit.

5. In an amusement apparatus, a supporting structure, an incline, a double set of rails forming in effect, a straightaway single track, each set of rails being alternately extended at intervals upon arcs of circles to form loops, the intersecting points of the 95 two sets of rails forming frogs, a passenger car equipped with swiveled trucks, the flanged traction wheels of which are adapted for travel over said rails under the influence of gravity, a set of wheels tracking 100 upon each set of rails, whereby upon reaching a loop, the rear set of wheels follow the straightaway track, and the front set of wheels follow the loop, so as to cause the car to automatically reverse itself bodily 105 without changing its course of transit.

In testimony whereof, I have hereunto signed my name.

THOMAS D. HOOPER, JR.
